UNITED STATES PATENT OFFICE.

HENRY PHELPS GAGE AND EMILIO PASCUCCI, OF CORNING, NEW YORK.

DESIGN FOR A LIGHT COVER GLASS.

55,777.

Specification for Design.

Patented July 13, 1920.

Application filed April 19, 1920. Serial No. 375,180. Term of patent 14 years.

To all whom it may concern:

Be it known that we, HENRY PHELPS GAGE and EMILIO PASCUCCI, citizens of the United States, residing at Corning, in the county of Steuben and State of New York, have invented a new, original, and ornamental Design for Light Cover Glasses, of which the following is a specification, reference being had to the accompanying drawing, forming part thereof.

The figure is a plan view of a light cover glass, showing our new design.

We claim:

The ornamental design for a light cover glass, as shown.

HENRY PHELPS GAGE.
EMILIO PASCUCCI.
